UNITED STATES PATENT OFFICE

JAMES H. GLEASON, OF WILLOUGHBY, OHIO, ASSIGNOR TO THE GAS MACHINERY COMPANY, OF CLEVELAND, OHIO, A CORPORATION OF OHIO

FUEL-CHARGING MECHANISM

Application filed November 11, 1927. Serial No. 232,571.

The invention particularly relates to charging devices by which a circumferentially uniform fuel bed is maintained automatically in the generator, furnace or other fuel consuming chamber by means of periodic fuel charges deposited therein by a distributor continuously rotated during the charging operation. Preferably, although not necessarily, each charge covers an area comprising only a small fractional part of the complete circumference of the fuel chamber. The accompanying showing of the invention relates to a form of such a device, for use with a gas generator, in which each charge covers substantially such a fractional part of the complete generator circumference that a plurality of charges will extend substantially once around the generator. To be more exact, the charged areas are so created that a plurality of charges will slightly more than comprehend one complete circumference whereby for each series of complete charging operations there will be a slight overlapping area whereby to obviate any possible low spots between successive charges.

The annexed drawings and the following description set forth in detail certain means illustrating my invention, the disclosed means, however, constituting but one of the various mechanical forms in which the principle of my invention may be embodied.

In said annexed drawings:

Figure 1 represents a vertical sectional view of my improved charging device, in combination with fragmentary portions of a standard water-gas generator, feeding means therefor, distributor cone actuating devices, etc., the view being taken in the planes indicated by line 1—1, Figure 3, and showing the relative positions of the several parts during a charging operation;

Figure 2 is a diagrammatic view illustrating how the successive coal charges are deposited in the generator;

Figure 3 is a horizontal section showing certain driving mechanism, the section being taken in the plane indicated by line 3—3, Figure 1; and

Figure 4 is a fragmentary view of the ele-

ments shown in Figure 1, certain parts being in section and certain other parts in elevation, the view distinguishing from Figure 1 in that Figure 4 shows the parts in non-charging position.

Referring to the annexed drawings in which the same parts are indicated by the same respective ordinals in the several views, a standard water-gas generator 1 formed with a dome 2 and a charging door 3 is adapted to be fed with fuel from my improved charging device. The latter is supported upon eccentrically mounted wheels 4 to permit dropping the charger on to the charging door 3. By any standard means fuel is fed automatically and periodically into a receiving hopper 5 from a spout 6, the hopper door being connected with the rod 7 actuated by suitable standard mechanism, usually a hydraulic cylinder. The receiving hopper 5 is flange-connected to a casing 8 within which is contained a cylindrical open-ended shell 9 formed with an inclined sector-shaped lower floor portion 10 adapted to act as a discharge chute for the fuel on to a bell distributor 14 supported by an actuating rod 12 which is periodically reciprocated vertically by a hydraulic cylinder 13. The sector-shaped chute 10 is formed with a lower collar member 11 surrounding the rod 12 and within which the latter is freely vertically movable, this collar 11 resting upon the top of the cone distributor 14 in the upper and non-charging position of the latter, as plainly shown in Figure 4, the cone distributor in this position serving also as a valve to prevent escape of the gases from the generator 1.

My improved charging device is designed to deposit one charge of fuel into the generator 1 during each down run of the apparatus. Furthermore, the device is designed to distribute this fuel automatically uniformly over the whole circumferential area of the generator 1. In the form of device herein described, the fuel is charged over a part only of the generator circumference at each charging operation, the shell 9 and hence the chute 10 being slowly and continuously rotated during the charging operation. When the valve 14 is lowered, the shell 9 follows

the same down to the point indicated in Figure 1 wherein it will be noted that an upper outwardly-extended portion 15 of the shell has been intercepted by a shoulder 16 formed 5 upon a shell member 17, the latter being secured at its upper end to the body 18 of a gear which will hereinafter be more fully described. The action is that, before the charging operation, the valve 14 has been 10 lowered into the dome 2 to a point substantially that shown in Figure 1; the shell 9 and the chute 10 having been lowered only to about a height substantially symmetrical with the charging door 3, whereby the shell 15 member 9 is lowered from the position shown in Fig. 4, in which its open upper receiving end is not in communication with the discharge side of the fuel-feeding device 25, to the position shown in Fig. 1, in which the fuel fed by the device 25 can fall by gravity 20 into the open top of the shell member 9. By means of the gear 18 having external teeth 19 meshing with a driven pinion 20, the shell 9 is slowly continuously rotating during the 25 charging operation. These means for rotating the shell 9 are interconnected with the means for operating the standard feeding drive, so as to rotate the shell 9 only a part of a complete rotation during a complete 30 charging operation, as will now be described.

The pinion 20 is secured to one end of a shaft 21 and to the other end of said shaft 21 is secured a bevel gear 22 adapted to mesh with a bevel gear 23 secured to a shaft 24 35 to which the spirally arranged standard feeding means 25 are secured. By well-known means, the feeding means 25 are actuated to feed the fuel by a step-by-step process during one charging operation through 40 the medium of a rod 26 connected at one end by suitable transmission devices to the shaft 24 and eccentrically connected at the other end to a shaft 27 of reduction gearing 28 which in turn is driven by motor 29. This 45 motor 29 by suitable switch devices is adapted cooperatively with the actuation of the hydraulic cylinders governing the movements of the rods 7 and 12, to feed fuel charges in the manner plainly indicated in 50 Figure 1 to the generator 1 at each down run and at a time when the valve distributor 14 is in its lowermost position, as is well known in the art. With the standard construction just described I have combined the described 55 means for rotating the shell 9, and hence the chute 10, a part of a rotation so as to cause the fuel to discharge through the lower opening 31 of the shell 9 and upon the valve distributor 14 over an area of about one-fifth of 60 the total circumference of the generator 1 for each entire charge of fuel fed by the vanes 25. As plainly illustrated in Figure 2, wherein the arrow indicates the direction of rotation of the shell 9 and the shaded area 65 30 indicates that portion of the generator

area covered by one charge, and the angle $a-b$ indicates exactly one-fifth of the whole circumference, it will be seen that I actually cover slightly more than one-fifth of the generator area by each charge so that upon the 70 repeated coverings of the same area of the furnace, every fifth charge will slightly overlap, resulting in the elimination of any low or otherwise defective areas between the 75 edges of successive charges.

The result of the operation of the apparatus described is automatically to facilitate even distribution of the fuel around the wall of the generator 1, as plainly shown in Figure 1, and eliminate entirely any undue dumping of fuel on any given area and also the building up of any low spots between successive series of charges or between any charges which are dumped on to adjacent 80 areas.

What I claim is:

1. Fuel-charging mechanism comprising a fuel-feeding device; means for supplying said device with fuel; a vertically-movable shell member with which said device communicates; means for periodically actuating said device to feed into said shell member; a vertically-reciprocable bell distributor below said shell member; means for periodically raising and lowering said bell, said shell member being supported upon said bell in the upper position of the latter, the bell forming a cone valve for the shell member in such upper position; means for intercepting and supporting the shell member intermediate the upper and lower positions of the bell as the latter is lowered; a discharge chute formed as an integral part of the shell member and interiorly thereof; and means for rotating said shell member from the periodic actuating means of said fuel-feeding device.

2. Fuel-charging mechanism comprising a fuel-feeding device; means for supplying said device with fuel; a vertically-movable shell member with which said device communicates in the lower position of said member; means for periodically actuating said device to feed into said shell member; a vertically-reciprocable bell distributor below said shell member; means for periodically raising and lowering said bell, said shell member being raised and lowered by said bell, the latter in its upper position supporting the shell member in a non-communicating position with reference to the fuel-feeding from said feeding device; means for intercepting and supporting said shell member as the bell distributor is lowered; a sector-shaped discharge chute secured within said shell member; and means for rotating said shell member concurrently with the actuation of said fuel-feeding device.

3. Fuel-charging mechanism comprising a fuel-feeding device; means for supplying

said device with fuel; a main casing with which said device communicates; means for periodically actuating said device to feed into said casing; a vertically-reciprocable bell distributor; means for periodically raising and lowering said bell; a vertically-movable shell member within said casing supported upon said bell in the upper position of the latter and adapted to receive the fuel charged into said casing; interengaging means formed upon said shell member and casing for stopping the downward movement of the shell member and supporting the latter before the bell reaches its lowermost position; a sector-shaped discharge chute secured within said shell member; and means for rotating said shell member concurrently with the actuation of said fuel-feeding device.

20 4. Fuel-charging mechanism comprising a fuel-feeding device; means for supplying said device with fuel; a main casing with which said device communicates; means for periodically actuating said device to feed into said casing, including a driving shaft; a vertically-reciprocable bell distributor; means for periodically raising and lowering said bell; a vertically-movable shell member within said casing supported upon said bell in the upper position of the latter and adapted to receive the fuel charged into said casing; interengaging means formed upon said shell member and casing for stopping the downward movement of the shell member and supporting the latter before the bell reaches its lowermost position; a sector-shaped discharge chute secured within said shell member; a gear member secured to and exteriorly of said shell member; and transmission elements driving said gear from said shaft of the actuating means for the fuel-feeding device.

Signed by me this 20th day of October, 1927.

45 JAMES H. GLEASON.
